UNITED STATES PATENT OFFICE.

HARRY C. REAGAN, OF PHILADELPHIA, PENNSYLVANIA.

MECHANISM FOR GAS-ENGINES.

1,209,497.

Specification of Letters Patent. Patented Dec. 19, 1916.

Application filed January 12, 1914. Serial No. 511,524.

To all whom it may concern:

Be it known that I, HARRY C. REAGAN, a citizen of the United States, residing in Philadelphia, Pennsylvania, have invented certain new and useful Improvements in Mechanisms for Gas-Engines, of which the following is a specification.

My invention relates to a device for filling the radiators or jackets of gas engines for 10 motor cars or like vehicles, and has for an object to provide a mechanism which though manually controlled for starting purposes, operates to automatically cause water or other cooling fluid to be drawn into the radiator or jacket, or to withdraw the cooling fluid from the radiator or jacket and replace the same by a fresh solution.

Heretofore it has been the common practice to fill or replace the cooling medium 20 for the engine jacket by removing the inlet cap of the radiator and pouring the fresh liquid in by means of a bucket, which method is not only tedious and troublesome, but results in great waste as well as often 25 soiling the clothes of the person handling the filling devices. By my present invention I have overcome the disadvantages accompanying this usual method of filling the radiator, and have provided a mechanism 30 which is simple and effective in use and may be readily attached to any type of vehicle.

As a further object of the invention, I have provided a means whereby the vehicle 35 may be washed or cleaned under pressure at times where a source of water under pressure cannot be obtained, this mechanism being particularly applicable for use in country districts or touring.

As a further object of the invention I 40 have provided a novel vacuum cleaning device for automatically removing dust and dirt from the upholstery, seats or floor of the vehicle.

As a still further object I have provided 45 a means whereby the interior of the vehicle may be supplied with heat in the winter or when needed in a cold climate.

It further consists in other novel features of construction, all as will be hereinafter 50 fully set forth.

For the purpose of illustrating my invention, I have shown in the accompanying drawings one form thereof which is at present preferred by me, since the same has been 55 found in practice to give satisfactory and

reliable results, although it is to be understood that the various instrumentalities of which my invention consists can be variously arranged and organized and that my invention is not limited to the precise arrangement and organization of these instrumentalities as herein shown and described.

Referring to the drawings: Figure 1 represents a side elevation of a radiator filling apparatus embodying my invention applied to an automobile; Fig. 2 represents a vertical section of the exhaust regulating mechanism; Fig. 3 represents a sectional elevation of the exhaust mechanism taken transversely of Fig. 2; Fig. 4 represents a perspective of an attachment for vacuum cleaning purposes.

Similar numerals of reference indicate corresponding parts.

1 designates the radiator of a motor vehicle having the customary water inlet 2 and cap 3, which latter when removed permits free access to the interior of the radiator for filling purposes. In the present instance I have tapped the inlet pipe 2 with a branch pipe 4 in which is a hand operated valve 5 connected to the pipe 6 which joins a conduit 7 leading to and terminating within an exhaust nozzle 8. This nozzle 8 is preferably cast integral with a four-way valve casing 9 of which 10 designates the inlet for the exhaust gases from the engine and 11 the outlet to the muffler 12. A branch pipe 13 is also in connection with the casing 9 and serves as an auxiliary discharge for the exhaust at certain times, and for a purpose which will later be explained.

14 designates a valve seat in the casing 9 arranged with reference to the inlet to the nozzle 8 and which in the present instance is controlled by a suitable valve 15 fixed to the rock-spindle 16 and operable by a crank 17. The auxiliary inlet to the pipe 13 is also provided with a valve seat 18 which is controlled by the valve 19 mounted upon the rock spindle 20, this latter being preferably independently operable by a crank arm 21 as will be understood. The cranks 17 and 21 are respectively operated by connecting rods 22 and 23 which lead to a convenient point of operation adjacent the operator of the vehicle.

24 designates an inlet pipe having communication with the interior of the radiator and controlled by a hand valve 25, the said

2
pipe 24 terminating exterior of the radiator in a union 26 or like coupling means by which a hose 27 may be connected thereto and serve to convey water or other cooling liquid to the radiator. Preferably the pipe 7 is provided with an extension 28 having a hand operated valve 29 and terminates in a coupling member 30 for a purpose which will be described in connection with the operation of the device. At another point in the pipe 7 there is a substantially similar inlet connection 31 provided with a valve 32 and coupling 33.

Under normal conditions of operation, namely with the radiator filled with cool water, the vehicle is operated in the customary manner, that is, the exhaust from the engine discharges directly into the muffler and the operation of the vehicle is not affected by the radiator filling mechanism embodying the features of my invention. If, however, for one reason or another, it becomes necessary to refill the radiator with a fresh cooling medium, or to replace a portion of the cooling medium by a new supply, it may be accomplished by attaching the hose section 27 to the coupling union 26 and lowering the free end into a source of water supply 34 or other cooling medium. The valves 5 and 25 are now opened to provide a circulation through the radiator and the operator, therefore, shifts the lever 22 so that the valve 15 takes the position shown in dotted lines in Fig. 2 to by-pass the exhaust 35 through the nozzle 8. It will be understood that the engine is running free or unclutched at this time. As the exhaust gases travel past the end of the pipe 7, a partial vacuum is created within the part of the radiator adjacent the discharge and consequently the contents of the radiator are drawn out under the atmospheric pressure upon the source of supply which of course also forces a fresh quantity of cooling liquid into the radiator. In this manner the radiator is quickly and easily filled and in addition any sediment or deposits within the radiator are carried out with the discharge fluid, the radiator being therefore at all times maintained clean and with the full radiating surface in effective operation.

As a modification of the refilling system the device may be operated to supply water for washing the vehicle, in which event the hose 27 is connected to the coupling 30, the valve 29 opened and another section of hose connected to the end of the nozzle 8, which is threaded as shown at 38 for the purpose, and the water mingled with the exhaust may be utilized to clean the body of the vehicle or other parts. As a further modification a hose member 35 having a vacuum suction nozzle 36 thereon may be connected at 33 so that the exhaust may be utilized to create a vacuum 65 for removing dust and dirt from the cushion-

ions, upholstery or other parts of the vehicle. The by-pass for the exhaust products by way of the outlet 13 is employed in cold weather for the purpose of heating the vehicle, and it will be understood that a suitable heater is located within the vehicle and receives the hot gases through the pipe 37, at which time the valve 19 is opened sufficiently to deflect all or a portion of the exhaust for heating purposes.

While I have here disclosed the apparatus as connected to the ordinary filling neck of the radiator, it will be understood that I do not wish to be limited or restricted to any particular point of connection, as obviously this may be varied to suit different conditions without departing from the spirit of my invention. Furthermore, it will be apparent that in practice it will be preferable to arrange the piping under the engine hood or otherwise vary the arrangement in order not to present an unsightly appearance. The entire mechanism may readily be concealed as will be understood by those skilled in the art. If desired the hose 27 may be attached to the pipe 24 as a substantially permanent part thereof, and the free end of the hose hung upon suitable hooks beneath the body until ready for use.

It will now be apparent that I have devised a complete unitary structure embodying the features set forth in the statement of invention, among which attention is directed to the advantageous result of a radiator maintained free at all times from mud or sediment deposits which ordinarily collect and reduce the effective area of the radiating surface very materially. Attention is further directed to the employment of the hose and suction member 36, since I contemplate a modified use of the same for ventilating purposes. This use is intended in connection with limousines or closed body vehicles, and comprises the fixture of the nozzle 36 at a convenient point within the body and adjacent the top thereof, and the valve controlling the exhaust is so set that a slight suction is at all times present in the nozzle and the air within the vehicle may thus be withdrawn, as will be understood.

While I have in the foregoing description referred to the radiator of a gas engine as the preferred embodiment of my invention, it will be understood that I do not wish to be limited in the use of the mechanism to this specific means, since I am well aware that the mechanism may be operatively connected to the water jacket of the gas engine to refill the same or cause a circulation of water therethrough. In fact, the exhausting mechanism may be connected to any suitable container for the cooling medium of a gas engine, and I do not desire the invention to be limited for use in connection with any specific appurtenance of a gas engine.

Having thus described my invention, what I claim and desire to secure by Letters Patent is:—

1. In a device of the character stated, a radiator having an inlet and an outlet, a filling device for said inlet adapted to communicate with a source of cooling medium, a casing adapted to receive an engine exhaust and having an outlet, a nozzle communicating with said casing through said outlet, means forming a communication between said radiator outlet and said nozzle, and means to control the opening and closing of the exhaust casing outlet to said nozzle. 45
2. In a device of the character stated, a radiator having an inlet and outlet, a filling device connected to said inlet and adapted to communicate with a source of cooling medium, a casing having communication with the exhaust of an engine, a nozzle connected to said casing, a fluid conducting medium having communication with said radiator outlet and projecting into said nozzle, and a valve for controlling communication between said casing and said nozzle. 50
3. In a device of the character stated, a radiator having an inlet and an outlet, a filling device connected to said inlet and adapted to communicate with a source of cooling medium, a valve for said filling device, a casing adapted to receive the exhaust of an engine, a nozzle communicating with said casing, a fluid conducting medium having communication with said radiator outlet and projecting into said nozzle, a valve for controlling the inlet to said medium, a muffler communicating with said exhaust casing, and means operable at will to bypass a portion or all of said exhaust from said muffler to said nozzle. 55
4. In a device of the character stated, a casing adapted to receive the exhaust of an engine and having a plurality of outlets, a muffler connected to one of said outlets, a discharge nozzle connected to another of said outlets, a conduit member connected to the remaining outlet, means operable at will for directing the engine exhaust to any of said outlets, in combination with a radiator, connections between said radiator and said nozzle for producing a partial vacuum in said radiator when the exhaust passes through said nozzle and a filling device connected to said radiator and having communication with a source of cooling medium. 60
5. In a device of the character stated, a casing adapted to receive the exhaust of an engine and having a plurality of outlets, a muffler connected to one of said outlets, a discharge nozzle connected to another of said outlets, means operable at will for directing the engine exhaust to either of said outlets in combination with a radiator, connections between said radiator and said nozzle for producing a partial vacuum in said radiator when the exhaust passes through said nozzle, a filling device connected to said radiator and having communication with a source of cooling medium and a suction device having communication with said casing for causing a circulation of air within the body of a vehicle. 65

In testimony that I claim the foregoing as my invention, I have hereunto signed my name this seventh day of January, A. D. 1914. 70

HARRY C. REAGAN.

In the presence of—

ROBERT M. BARR,
C. H. WISSMANN.
